UNITED STATES PATENT OFFICE.

CHARLIS METREWITZ, OF CHICAGO, ILLINOIS.

WASHING-MACHINE.

1,214,574.

Specification of Letters Patent. Patented Feb. 6, 1917.

Application filed June 19, 1916. Serial No. 104,468.

To all whom it may concern:

Be it known that I, CHARLIS METREWITZ, a subject of the Czar of Russia, residing at Chicago, in the county of Cook and State 5 of Illinois, have invented certain new and useful Improvements in Washing-Machines, of which the following is a specification.

My invention relates to improvements in washing machines and more particularly to 10 machines of this class having receptacles of an oscillatory or rocking type.

My improved machine is particularly adapted to handle household washing and to facilitate the several operations of washing, rinsing, and wringing by incorporating mechanisms for performing these operations in a single compact machine.

The objects of the invention are to produce a comparatively simple, durable and 20 reliable machine which may be driven either by hand or by power. To so arrange the several mechanisms for performing the operations of washing, rinsing and wringing that the clothes or other material being operated upon may be conveniently moved from the washing receptacle to the rinsing receptacle and then to and through the wringer, and to so locate and position the parts of the machine that the movable elements may be readily exposed for inspection, 30 repair or replacement. These and other objects I accomplish as hereinafter described in the following description and as particularly pointed out in the appended claims, 35 reference being had to the accompanying drawings in which an embodiment of the invention is shown.

In the drawings Figure 1, is a side elevation of my improved washing machine, the 40 hinged doors on that side of the machine being broken away to expose the interior construction. Fig. 2, is a side elevation of my improved washing machine, looking at the side opposite the side shown in Fig. 1, 45 and the hinged doors on that side being also broken away to expose the interior construction. Fig. 3, is a top view of the improved washing machine. Fig. 4, is a vertical longitudinal section through the washing machine taken on line 4—4, Fig. 3. Fig. 5, 50 is a detached horizontal section through the hollow washing receptacle taken on line 5—5 Fig. 4, and looking downward in the direction of the arrows in said Fig. 4. Fig. 6, 55 is a fragmentary longitudinal vertical section through the washing machine to illus-

trate the oscillatory toothed rack for rocking the washing receptacle. Fig. 7, is a fragmentary elevation of the wringer attachment of my improved washing machine. 60 Fig. 8, is an enlarged fragmentary view of a portion of the power transmitting mechanism. Fig. 9, is an enlarged fragmentary view partially in section to illustrate the clutch mechanism for connecting the 65 wringer to the power transmitting mechanism. Fig. 10, is a fragmentary section on line 10—10 Fig. 6, through the lever to show the locking band.

In referring to the embodiment of my improved washing machine shown in the accompanying drawings in detail, like numerals designate corresponding parts.

While my improved machine is principally designed for household use, it may if 75 desired be used in laundries, hotels and other places where it is necessary to wash comparatively large quantities of clothes or other material each day.

As shown, the frame of the machine is upright and longitudinally elongated and consists of two parallel vertical side members 1 and 2, which are held in separated arrangement by a series of transverse connections.

Referring to Fig. 4, it will be noted that 80 two troughs are arranged in the upper portion of the frame one being located at one end and forming a catch trough 3 for the water from the washing receptacle which is mounted vertically over it, and the other 85 which is smaller than the catch trough 3, being arranged near the center of the frame and constituting a rinsing basin 4, into which the clothes are dropped as they are removed 90 from the washing receptacle. Both of the 95 troughs 3 and 4 are provided with drain taps 5 and 6, and a shallow tray 7 is slidably mounted in the frame beneath the taps. The 100 tray is also provided with a drain tap 7.

The side frame members 1, and 2, have 105 vertical extensions 8, projecting upward from near one end and a washing receptacle 9 is mounted between said extensions so as to oscillate therein. I prefer to make the washing receptacle in a hollow oval form as shown in Fig. 4 in cross section, and provide it with a series of inwardly extending ribs 10, arranged at intervals on the interior of the receptacle over which the clothes bump as the receptacle is rocked. A removable cover 11, is fitted in the top of the receptacle through which clothes are intro-

duced into or removed from the same. The extensions 8, are connected at their upper extremities by a horizontal cross bar 12, and a rocking lever 13 is pivotally hung from said cross bar. This lever is provided with an enlarged loop like intermediate portion 14, which is transversely elongated and is provided on its lower inner edge with a cross rack 15 of teeth which mesh with a pinion 16, mounted on one of the short shafts 17, extending from the ends of the washing receptacle which are journaled in the extensions 8, as shown in Fig. 6. The side frame members are recessed on their exterior to provide hollow spaces 18, and these spaces are normally closed by hinged doors 19. Owing to this construction, hollow spaces of narrow width are provided on each side of the frame in which portions of the power transmitting mechanism are located, as will be more clearly hereinafter described.

The machine may be either operated by power or hand and in Fig. 4 an electric motor 20 is shown, the shaft 21 of which carries a worm 22, which meshes with a gear wheel, 23 on a transverse shaft 24. The shaft 24 is connected by belt 25, and grooved wheels 26 and 27 to a second transverse shaft 28, which in turn is connected by gear wheels 29 and 30 to a third shaft 31. The two first mentioned shafts 24 and 28 are comparatively short, while the third shaft is long and extends transversely through the machine to the opposite side thereof where a grooved wheel 32 is mounted upon its projecting end. The lower end of the lever 13, is operatively connected to the wheel 32 by a connecting rod 33 so that rotation of the wheel 32 will rock the lever. To provide means for adjusting the point of attachment of the connecting rod 33, to the lever a series of holes 34 are formed in any one of which the pivot 35 may be inserted, and to facilitate disconnecting the rod from the receptacle, the lever may be formed with an extra pivoted arm 36, which is pivoted at its upper end to the lever and normally held immovably to the lever by a slip band 37. When it is desired to stop the washing receptacle from rocking without stopping the machine, the band 37 is slipped down which permits the arm 36 to oscillate without moving the lever 13. The washing receptacle is protected and inclosed by hinged screens 38 which can be opened when it is desired to introduce or remove clothes into or from the washing receptacle. The lever 13 is yieldingly balanced between two opposed springs 39, which are connected to opposite sides of the loop portion 14, and hang from oppositely extending wires 40, as shown in Fig. 2. Besides the electric motor the machine may be operated by hand by turning a handle 41, shown in dotted lines

in Fig. 1, which is fitted on a shaft 42, journaled in the end of the frame. This shaft 42, carries a grooved wheel 43, which is connected by a belt 44, with the grooved wheel 27 on the shaft 28. At the end of the frame opposite the shaft 42, is detachably mounted, a wringer which is constructed substantially as shown in Figs. 1, 4 and 7 having an upright rectangular frame 45 and a large main upper roller 46 and two small lower rollers 47 and 48, arranged horizontally side by side and mounted in said frame. The main roller is yieldingly pressed down upon the smaller lower rollers by zig-zag bent springs 49, and thumb screws 50 are arranged in the top of the frame for the purpose of adjusting the tension of the springs. A grooved wheel 51 is mounted on a short shaft 52, which is connected by a belt 53 to the grooved wheel 32, and transmits power to the wringer through a clutch. The preferable form of clutch is shown in Fig. 9 and consists of two clutch members 54 and 55, a shifting lever 56, and a transverse arm 57 at the upper end of said lever which is held in contact with a locking part 58, by a spring 59 and is provided with notches 60 into which the part 58 is adapted to snap. The clutch is shifted into or out of engagement by manually depressing and then laterally moving the arm 57.

The operation of my improved machine will be easily understood from the foregoing description.

The rollers of the wringer are connected together by meshing gear wheels 61, 62 and 63 so that they will rotate in unison.

Referring to Fig. 5, the interior of the washing receptacle may if desired be divided into several compartments by longitudinal partitions 64 and 65, thus providing separate spaces for different goods being washed.

While I illustrated and described a preferred form of construction for carrying my invention into effect, the same is capable of a wide range of variation, alteration, modification and change without departing from the spirit of the invention, I therefore do not wish to be limited to the construction herein shown and described, but desire to avail myself of all such variations, alterations, modifications and changes as fairly fall within the scope of the appended claims or may be construed to come within the same by involving the doctrine of equivalents.

What I claim as my invention and desire to secure by Letters Patent is:—

1. In a machine of the class described in combination, a frame, a washing receptacle mounted in said frame so as to rock on a horizontal axis, a standard on said frame projecting above the level of said axis, an oscillatory lever pivoted on the upper part

of said standard and extending downwardly therefrom, said lever having a loop-like portion provided with a toothed rack and the washing receptacle having a pinion 5 meshing with said rack, arms extending outwardly and downwardly from said standard, and springs connecting said arms with the ends of the loop portion.

2. In a machine of the class described in 10 combination, a frame, a washing receptacle mounted in said frame so as to rock on a horizontal axis, a standard on said frame projecting above the level of said axis, an oscillatory lever pivoted on the upper part 15 of said standard and extending downwardly therefrom, said lever having a loop-

like portion provided with a toothed rack, and the washing receptacle having a pinion meshing with said rack, arms extending outwardly and downwardly from said standard, springs connecting said arms with the ends of the loop portion, a reciprocating link for oscillating said lever, an auxiliary lever pivoted to said first mentioned lever and a sleeve slideable on said auxiliary lever 20 for operatively connecting and disconnecting the same from said first mentioned lever.

In testimony whereof I have affixed my signature.

CHARLIS METREWITZ.
